UNITED STATES PATENT OFFICE

CHARLES S. CUSHMAN, OF BARRE, VERMONT

STONE POLISHER

Application filed January 6, 1927. Serial No. 159,457.

This invention relates to new and useful improvements in polishing machines, and particularly to machines for polishing stone, such invention being an improvement over 5 my prior Patent #1,491,790, issued April 29, 1924.

In the prior patent the motor was bolted to a ring, said ring being properly supported in a grooved ring within the casing. 10 The motor was provided with a gear which meshed with a ring gear on the casing, and whereby the casing was rotated, to rotate the polishing element carried by the bottom of the casing.

15 Also, the casing of the motor was provided with straps engaged with a bar, and said bar was mounted on a vertical support for adjustment vertically thereon.

The present device contemplates a different, and more efficient means of connecting the motor to the ring, whereby the entire device may be elevated or lowered with respect to the hanger of the device.

Another object is to provide a device of 25 this character which is capable of being readily removed, and another device for polishing a stone substituted therefor.

A still further object is to provide a device of this character wherein a plurality 30 of stone polishing elements may be supported on the same carriage, thus permitting different parts of the surface of a large stone to be polished at the same time, or to permit work on several pieces of stone simultaneously.

Other objects and advantages will be apparent from the following description when taken in connection with the accompanying drawing.

40 In the drawing:

Figure 1 is a front elevation of the stone polishing device.

Figure 2 is a side elevation of the same, partly in section.

45 Figure 3 is a horizontal sectional view on the line 3-3 of Figure 1.

Figure 4 is a vertical sectional view on the line 4-4 of Figure 1.

50 Referring particularly to the accompanying drawing, 10 represents a portion of an

elevated track on which is supported the traveling carriage 11, said carriage being adapted to support the elements forming the subject-matter of the present application.

55 Mounted on each side of the carriage are the vertically aligned brackets 12, and disposed vertically through each pair of said brackets is a tubular member 13, having the longitudinal slots 14, in the opposite sides, intermediate the brackets. The upper 60 bracket 12 is provided with an apertured lug to which is connected one end of a spring 15.

65 The polishing unit includes a casing 16, having a ring gear 17 on its upper edge. Within the casing is disposed a grooved ring 18, and arranged within said ring is a runner ring 19. A flange 20, carried by the side of the casing, bears on a portion of the upper face of the runner ring, whereby to 70 maintain the latter within the ring 18, and against movement from the casing. On the inner portion of the upper face of the ring 19 is secured a second ring 21, and connected with and extending upwardly from the ring 75 21 is a yoke 22, having a socket 23 in its upper end. Disposed within the casing and having securing lugs 24, is a motor 25, such lugs resting on the ring 21, and being bolted, together with the ring 21, to the ring 19. 80 On the motor shaft is a gear 25' which meshes with the ring gear 17. Secured within the socket 23 is the lower end of a vertical hollow shaft or rod 26, the upper portion of the rod being slidably disposed 85 through the before-mentioned tubular member 13, and being provided with a transverse pin 27, carrying rollers 28, which play in the slots 14, of the tubular member 13.

90 Secured to the bottom of the casing 16 is a casting 29, which has the downwardly extending yoke 30, the arms of which are pivotally connected with a block 31 pivotally carried by the stone wheel carrier 32, whereby said stone wheel is readily capable of 95 adjusting itself to various unevennesses on the surface of the stone being polished, due to the fact that said casting is a portion of the universal joint which includes the said block.

On the yoke 22, adjacent the socket 23, is an apertured lug 33, to which is connected one end of a chain 34, the other end of the chain being connected to the other end of the spring 15, and whereby the casing, containing the motor, together with the stone wheel, may be maintained in proper contact with the stone when moving over uneven places on the surface of the stone.

When it is desired to replace the polishing unit with another unit of greater or lesser size, or a unit of different abrasive qualities, the operator removes the pin 27, to lower the stone polishing unit, and permit the rod 26 to slide downwardly out of the tubular member 13. The hoist is disconnected from the polishing unit, and connected to the unit which is to be substituted, after which the new unit is elevated into place, and the pin 27 replaced through the slots of the member 13, and the rod 26, of the substituted unit. It will be noted that the rod 26 is provided with a series of openings 27', for interchangeably receiving the pin 27, whereby to permit the polishing unit being supported at the desired height. When a small polishing wheel was used in a device of this character, heretofore, the polishing unit, including the motor, became quite top-heavy, or overbalanced. This was because of the more or less flexible support for the unit. The particular manner in which the present device is constructed provides for holding the polishing unit in a rigid upright position, thereby overcoming any tendency of such unit removed latterly, due to the light weight of the small polishing wheel.

What is claimed is:

A polishing device including a horizontally movable carriage, vertically aligned guides on the carriage, a vertical tubular member extending between the guides and having its ends secured therein, said tubular member having longitudinal slots in opposite sides thereof between the guides, a polishing wheel, a motor for driving the wheel including a casing, a vertical shaft attached to the casing and slidably disposed through said tubular member, and a transverse pin removably disposed through the shaft and having its ends provided with rollers disposed in said slots to maintain the motor operated unit in a rigid upright position, whereby to prevent overbalancing thereof when a small polishing wheel is used.

In testimony whereof, I affix my signature.
CHARLES S. CUSHMAN.
